UNITED STATES PATENT OFFICE

ERNEST NADOR, OF ST. LOUIS, MISSOURI

BOAT

Application filed July 29, 1930. Serial No. 471,508.

The present invention relates to a boat and has for its prime object to provide a structure which is simple, compact and convenient in its arrangement of parts, light in weight, 5 capable of being easily and quickly assembled and disassembled, and being thoroughly efficient, reliable and safe in use and operation. Another object of the invention is to provide, in a manner as hereinafter set forth, 10 a boat embodying a pair of spaced, parallel pontoons having connecting rods extending therebetween and detachably secured thereto, the securing means for the connecting rods being mounted for longitudinal adjustment 15 on the pontoons.

Another important object of the invention is to provide a boat of the character described including a pair of spaced, parallel pontoons formed from a flat sheet of metal rolled to 20 tubular form and provided with a joint for the abutting edges of the flat sheets for coaction with the connecting rod securing means or clamps whereby said clamps may be expeditiously adjusted longitudinally on the pontoons.

All of the foregoing and still further objects and advantages of the invention may become apparent from a study of the following specification, taken in connection with the 30 accompanying drawings wherein like characters of reference designate corresponding parts throughout the several views, and wherein:

Figure 1 is a top plan view of a boat embodying the features of my invention,

Figure 2 is a side elevation thereof,

Figure 3 is a vertical transverse section taken substantially on the line 3—3 of Figure 1,

Figure 4 is a longitudinal vertical section through one of the pontoons,

Figure 5 is a vertical fragmentary section taken longitudinally substantially on the line 5—5 of Figure 1,

Figure 6 is a vertical transverse section

taken substantially on the line 6—6 of Figure 1,

Figure 7 is a bottom plan view of the body,

Figure 8 is an enlarged detail view of one of the clamps.

Referring to the drawings in detail, it will be seen that the numerals 5 denote elongated, spaced, parallel, coextensive, hollow pontoons which are open at their opposite ends and have mounted thereon the substantially conical shaped heads 6. These tubes or pontoons are divided into watertight compartments by means of the partitions or bulkheads 7. Each of the pontoons 5 are formed from a flat sheet of metal which is rolled to tubular form with the longitudinal edges of the sheet disposed in abutting engagement with each other as best seen in Figures 1, 3 and 6 of the drawings.

Elongated metallic connecting strips 1 of metal are disposed within each of the pontoons and extend beneath the longitudinal marginal portions of the rolled sheets, said marginal portions are connected to the strips 1 by the staggered screws 2. Disposed longitudinally over the seam on each tube or pontoon is a clamping bracket 8 adjacent the front ends thereof and three brackets 9, 10 and 11 on the intermediate portions of said tubes or pontoons. The brackets 8, 9, 10 and 11 are identical in construction and, as best seen in Figure 8 of the drawings, comprise a stationary jaw 3 mounted on the oppositely extending apertured feet 4 and having hingedly mounted thereon a swingable jaw 4' which is secured in locking position by the swingable keeper 4''.

The foot portions of the clamps are each provided with a plurality of openings which are staggered to register with the openings in the tubes or pontoons 5 in which the securing screws 2 are anchored. It will thus be seen that the securing screws 2 are utilized to anchor the brackets 8, 9, 10 and 11 in position on top of the pontoons 5 and said

brackets may be mounted at any desired point longitudinally on the pontoons.

A rod 12 is disposed across the front ends of the pontoons 5 and adjustably clamped between the jaws 3 and 4 of the brackets 8. 5 Rods 14, 15 and 16 are disposed across intermediate portions of the pontoons 5 and adjustably clamped in the pairs of brackets 9, 10 and 11 respectively. Standards 17 rise from the rod 15 to receive oar locks 18 in their upper ends. Braces 19 extend from the upper portions of the standards 17 to the rods 14 and 16 while braces 20 extend from the upper ends of the standards to intermediate portions of the rod 15. 15

An outboard motor support 22 is mounted across the rear portion of the pontoon 5, for supporting an outboard motor 23. Forwardly diverging braces 25 extend between the rod 22 and the rod 16 as clearly seen in Figure 1 of the drawings.

A body 26 which may be of collapsible construction is provided on its bottom with a plurality of pairs of brackets 27 adapted to 25 clamp on the rods 14, 15 and 16 for adjustably and detachably mounting the body on said rods.

From the above detailed description, it will be seen that I have devised a novel 30 form of boat wherein the pontoons may be adjusted toward or away from each other to a limited extent and wherein the parts are capable of ease of assembly and disassembly.

The brackets 27 are identical in construction to the brackets 8, 9, 10 and 11 and are thus interchangeable but said brackets 27 are not mounted for adjustment on the bottom of the body 26. By reason of the adjustability of the brackets 9, 10 and 11 on 40 the pontoons 5 the body 26 may be disposed at any desired point in the longitudinal length of the pontoons. This constitutes an important and desirable feature of the present invention as does also the novel means 45 whereby the brackets 8, 9, 10 and 11 are mounted for longitudinal adjustment on the pontoons 5.

It is thought that the construction, utility and advantages of this invention will now be 50 quite apparent to those skilled in this art without a more detailed description thereof.

The present embodiment of the invention has been disclosed in considerable detail merely for the purposes of exemplification 55 since in actual practice it attains the features and advantages enumerated as desirable in the statement of the invention and the above description.

It will be apparent that changes in the 60 details of construction, and in the combination and arrangement of parts may be resorted to without departing from the scope of the invention as hereinafter claimed or sacrificing 65 any of its advantages.

Having thus described my invention, what I claim as new is:

1. In a boat of the class described, a pair of spaced parallel coextensive pontoons, a rod across the front portions of the pontoons, three spaced parallel rods across the intermediate portions of the pontoon, a collapsible body on said three last mentioned rods, a standard rising from each end of the center of the three rods, bracing means associated therewith, and oar locks in the upper ends of the standard. 70

2. In a boat of the character described, a pair of spaced, parallel pontoons, each pontoon comprising an elongated metallic sheet rolled to tubular form with its longitudinal edges in abutting engagement, a connecting strip disposed longitudinally in each pontoon against the adjacent marginal portions of the metallic sheets, said marginal portions and the strips having registering openings, brackets disposed on the pontoons and having openings therein in registry with the openings in the marginal portions and the strips, anchoring screws connecting the marginal portions and the strips together and anchoring screws extending through the openings in the brackets and through certain of the openings in the marginal portions and the strips, and connecting rods extending between the pontoons and anchored to the brackets. 80

3. In a boat of the character described, a pair of spaced, parallel pontoons, each pontoon comprising an elongated metallic sheet 100 rolled to tubular form with its longitudinal edges disposed in abutting engagement with each other, a connecting strip disposed longitudinally in each pontoon and engaged with the adjacent marginal portions of the sheets, said marginal portions and the strips being provided with staggered registering openings, brackets mounted for longitudinal adjustment on the pontoons, each of said brackets comprising a stationary jaw, a swingable jaw hingedly mounted thereon, and oppositely extending feet for engagement on the pontoons and having a plurality of staggered openings adapted to be selectively registered with the openings in the marginal portions and the connecting strips, anchoring screws extending through the registering openings in the bracket feet, the marginal portions and the strips and additional anchoring screws extending through the registering openings in the marginal portions and the strips, rods extending transversely between the pontoons, and clamped to the brackets, and a body supported on certain of the rods. 105

4. In a boat of the character described, a pair of spaced, parallel pontoons, pairs of brackets disposed on the upper sides of the pontoons, means for anchoring the brackets for longitudinal adjustment to the pontoons, 115

120

each bracket comprising a stationary jaw and a swingable jaw hingedly connected to the stationary jaw and further including means for releasably securing the swingable jaw in clamping position, connecting rods extending transversely between the pontoon and adjustably clamped in the pairs of brackets, a body mounted on certain of the connecting rods, and clamps mounted on the body for detachable engagement with said certain rods for adjustably securing the body thereto.

In testimony whereof I affix my signature.
ERNEST NÁDOR.
